The ornamental design for a liquid soap dispenser tube with checkvalve and two holed multi-sized bottle cap, as shown and described.

DESCRIPTION

FIG. 1 is a front elevation view of a liquid soap dispenser tube with checkvalve and two holed multi-sized bottle cap that comprises my new invention;

FIG. 2 is a top perspective view of the stoppers separated from the hose with checkvalve for ease of illustration;

FIG. 3 is a bottom perspective view thereof;

FIG. 4 is a perspective view with the stoppers removed from the hose with checkvalve and placed in the center of the hose with checkvalve; and,

FIG. 5 is a perspective view with the stoppers removed from the hose in an inverted position and placed in the center of the hose with checkvalve.
